UNITED STATES PATENT OFFICE.

JOSEPH ROGER WHITE, OF WASHINGTON, DISTRICT OF COLUMBIA, ASSIGNOR TO THE GRAPHOSCOPE COMPANY, OF WASHINGTON, DISTRICT OF COLUMBIA, A CORPORATION OF DELAWARE.

PICTURE-PROJECTING APPARATUS.

1,312,374.

Specification of Letters Patent.

Patented Aug. 5, 1919.

Application filed December 16, 1914. Serial No. 877,535.

To all whom it may concern:

Be it known that I, JOSEPH ROGER WHITE, a citizen of the United States, residing at Washington, in the District of Columbia, 5 have invented certain new and useful Improvements in Picture-Projecting Apparatus, of which the following is a specification, reference being had therein to the accompanying drawing.

10 This invention relates to projecting pictures by means of arc lights. With the usual alining carbons approximately perpendicular to the projecting line, the current forms in one carbon a cup-like depression interfering with direct transmission of a portion of the light. I have found that a different arrangement of the carbons lends itself to the requirements of projection and gives material increase in efficiency.

20 In the accompanying drawings,

A represents a projecting lens, B a picture to be projected, C a condensing lens, and D a common rod-like carbon or electrode in the line of projection. E, E' design-

25 nate two similar carbons the axes of which diverge oppositely in the same plane from the working end of the carbon D and in such position that they intercept practically no rays which it is desirable to have fall 30 upon the condensing lens. F represents any suitable source of current from which circuit is made through a conductor G, the carbon D, the arcs at the gaps, the carbons E, E', and the conductor branches G', back

35 to the source. In the branches leading from the carbons E, E', respectively, are interposed rheostats H, H'. When suitable current passes from the source, two arcs are formed from the carbon D to the carbons E, E', and the conductor branches G', back

40 to the source. It is evident that the electrodes are not necessarily carbons in rod form, so long as the luminous areas upon the carbon D pass unobstructed to the condensing lens C. The resistances in the two branches may be unequal within somewhat wide limits without 45 destroying or interfering with the formation of the two arcs.

It is evident that the electrodes are not necessarily carbons in rod form, so long as the light from the luminous areas is not obstructed by any of the three electrodes; and this condition being observed, the number 50 of electrodes may be increased.

What I claim is:

55 1. In picture projecting apparatus, the combination with suitable lenses, of an arc

light electrode in the axial line of the lenses, and a plurality of other electrodes coacting with the electrode first mentioned to form a plurality of arcs in parallel and lying outside the paths of rays passing from the luminous area on the first electrode to said lenses, said electrodes lying in the same plane in position to form on the end of the axial electrode a single central crater or luminous spot.

60 65

2. In picture projecting apparatus, the combination with suitable lenses of an arc light electrode lying in the axial line of the lenses, a plurality of other electrodes in the same plane diverging from the point where said line meets the first mentioned electrode and in position to coact therewith to form a single central luminous spot on the end of the electrode first mentioned, a source of current, a conductor leading from said source to the first electrode, conductors leading from said other electrodes, respectively, back to the source, and rheostats interposed in the conductors last mentioned, 70 75 80

3. In picture projecting devices, the combination of alined projecting and condensing lenses, of an arc light electrode having a point in the axial line of the lenses, and a plurality of divergent companion electrodes in parallel 85 in position to form with the first electrode arcs diverging from a common central point on the end of the latter, and all lying outside the path of rays passing from the luminous area of the first mentioned electrode to 90 the condensing lens.

4. The combination with a suitable arc light electrode, of a series of electrodes arranged beyond the end of said electrode, forwardly diverging from the extended axis 95 thereof and in position for forming therewith arcs in parallel extending from a common luminous central spot on the end of the electrode first mentioned.

5. The combination with a suitable arc light electrode, of a series of electrodes arranged about the electrode first mentioned in position for forming therewith arcs in parallel diverging from a common luminous central spot on the end of the electrode first 105 mentioned, and a lens in position to receive from the luminous area on the first electrode direct, unobstructed luminous rays of light.

6. The combination with a suitable arc 110

2
light electrode, of a series of electrodes arranged beyond the end of the electrode first mentioned, forwardly diverging from the extended axis thereof and in position for forming therewith arcs in parallel diverging from a common luminous central spot on the end of said first mentioned electrode, a source of current, a conductor leading from said source to the first electrode, conductors leading from the other electrodes, respectively, back to said source, and rheostats interposed in the conductors last mentioned, respectively.

7. The combination with a suitable arc
15 light electrode, of a series of electrodes ar-

ranged in parallel about the electrode first mentioned, beyond the end of said electrode, forwardly diverging from the extended axis thereof and in position to form therewith arcs having their ends in the same plane and all diverging from a common central luminous spot on the end of the electrode first mentioned. 20

In testimony whereof I affix my signature in presence of two witnesses.

JOSEPH ROGER WHITE.
